UNITED STATES PATENT OFFICE.

FRED A. LUND, OF HOUSTON, TEXAS.

ELECTRIC DISPLAY SIGN.

Application filed August 1, 1924. Serial No. 729,551.

To all whom it may concern:

Be it known that FRED A. LUND, a citizen of the United States, residing at Houston, in the county of Harris and State of 5 Texas, has invented new and useful Improvements in Electric Display Signs, of which the following is a specification.

It is the purpose of the present invention to provide, in a display sign, a construction 10 particularly adapted for use in show windows and the like for advertising.

Another purpose is to provide a display sign which is portable and can be located in any portion of a show window found convenient 15 for displaying advertisements, the construction including a plurality of sets of letters, which are small or of various sizes whereby extensive advertisements may be on display.

20 Still another purpose is the provision of a frame including a rabbet for the reception of two sections of glass between which the advertisement made up of letters may be arranged, the inner face of the inner glass section being colored, in conjunction with 25 means for exerting pressure upon the two glass sections to hold the letters in position after the advertisement has been made up.

A further purpose is the provision of 30 means for permitting the glass sections to be removed so as to permit the advertisement between the glass sections to be changed.

A still further purpose is the provision of 35 a display sign including a frame with means on the interior thereof to support an electric bulb for lighting the interior whereby the advertisement will stand out at night as well as in the day time, the inner surface of the frame being highly glazed, polished or 40 otherwise treated in order to constitute reflecting means for the light.

It is to be understood that the particulars herein given are in no way limitative and that, while still keeping within the scope of 45 the invention, any desired modifications of detail and desired proportions may be made in the apparatus according to the circumstances.

The invention comprises further features 50 and combinations of parts to be hereinafter set forth, shown in the drawings and claimed.

In the drawings:

Figure 1 is a perspective view of the improved display sign construction in accordance with the invention.

Figure 2 is a longitudinal sectional view on line 2—2 of Figure 1.

Figure 3 is a vertical cross sectional view on line 3—3 of Figure 1. 60

Figure 4 is a face view of the frame with the beading or molding frame removed, showing the glass holding cleats engaging the loops of the main frame.

Figure 5 is a detail view of a portion of 65 the casing 1, showing the glass sections 6 and 7, the retaining cleat 14 and the block 15, and showing the reinforcing metal strip for the cleat to retain the block against the glass section. 70

Figure 6 is a detail view of a portion of 75 the wood frame 2 and the cleat 14 with the reinforcing metal strip and showing the wedge 16.

Referring to the drawings, 1 designates a frame which may be of any suitable size or shape and constructed of any suitable sheet metal, preferably tin or sheet aluminum. The frame is preferably rectangular, the exterior of which may be painted or otherwise decorated, and secured to the sides and ends of the sheet metal frame adjacent the forward edges is a wooden frame 2. Suitable screws 3 secure the wooden frame in position. The end portions of the sides and ends of the wooden frame are mitered, as shown at 4. The wooden frame has a rabbet 5 for the reception and support of two sections of glass, an inner section 6 (the inner face of which is painted or otherwise colored, preferably white) and an outer plain section 7. 80 85

Some suitable instrument may be used to cut guide lines 8 in the painted surface of the bottom section of the glass to act as 90 guides for arranging the letters 9 of the advertisement. Any number of guide lines may be employed and it is also obvious that the main frame may be of any size. In fact, it may be of such size to be moved from one place to another in a show window or it may be made relatively large and capable of occupying but one position in a show window. In this latter case, a number of advertisements may be disclosed by the present form of display sign. In fact, the larger the glass, the more advertisements may be displayed. 95 100 105

The bottom rail of the wooden frame and the lower wall of the sheet metal main frame 110 have registering notches or cut-away portions 10 and 11 to permit of the reception of

the fingers to permit the removal of one or both of the glass sections.

Secured to the wooden frame, as at 12, are U-shaped retaining loops or holders 13 which project outwardly from the wooden frame for the reception of the ends of the wooden cleats or glass retaining bars 14. These cleats or bars are disposed adjacent the longitudinal rails of the wooden frame, 10 and carried by certain of their faces are blocks 15 which are elongated and act to bear upon the outer glass section at locations adjacent its upper and lower edges, thereby exercising continuous pressure of 15 one glass section toward the other for the purpose of frictionally retaining the letters forming the advertisement in place. The letters may be made of any suitable material, preferably pasteboard or other fiber or the 20 like, non-transparent so that the letters will stand out prominently when the interior of the main frame is illuminated.

In order to insure maintaining a constant pressure of the blocks on the cleats upon 25 the glass sections, suitable wedges 16 may be inserted between the ends of the cleats and the outer walls of the retaining loops or holders. The removal of these wedges will permit the cleats to be removed and the 30 glass sections may be subsequently removed.

A molding frame 17 constructed of any 35 suitable metal, preferably sheet copper or the like, is provided to engage around the margin of the main frame, acting to cover the retaining loops or holders and to cover 40 the cleats. This molding frame is beveled and of the shape in cross section shown in Figures 2 and 3. This molding frame is secured to the main frame by means of screws 18.

A suitable porcelain socket 19 is mounted on the upper wall of the main frame for the 45 reception of an electric light bulb 21 and secured upon the outer face of the top of the main frame is a similar socket 20 which is adapted to receive the usual plug (not shown) which may be connected by a wire (not shown) with the source of electrical supply. The two sockets are electrically 50 connected, as at 22, there being suitable screws 23 passing through the top of the main frame and through ears of the sockets to hold the sockets in position.

In order to insure pressure of the blocks 55 15 on the glass sections 6 and 7, metal reinforcing spring strips 24 are secured by bolts 25 to the cleats 14. The ends of the metal reinforcing spring strips provide a steady pressure on the cleats and have their termi-

nals overbent, as at 26, to overlie the ends 60 of the cleats 14.

A suitable wooden frame 27 of an ornamental character is provided. This frame is rabbeted, as shown, to engage over the molding frame 17. The wooden frame 27 may have any ornamental shape and be provided with a wooden veneering, such as quartered oak, mahogany or the like. The surface of the veneering may be highly polished so as to present a very neat appearance. 70

The invention having been set forth, what is claimed is:

1. A display sign comprising a main frame, an auxiliary frame secured therein adjacent its forward margin and provided 75 with a rabbet, a pair of glass sections engaging said rabbet, outstanding retaining loops on the auxiliary frame, cleats engaging said loops and provided with means bearing upon the outer glass section to insure constant 80 pressure of the outer glass section against the inner glass section an advertising exhibit between the two glass sections and frictionally engaged by them, and a molding covering said cleats and cleat retaining loops. 85

2. A display sign comprising a main frame, an auxiliary frame having a rabbet and secured in the main frame adjacent its forward margin, a pair of glass sections engaging said rabbet, longitudinal cleats carrying blocks bearing upon the margin of one of the glass sections to insure pressure 90 between it and the other glass section, an advertising exhibit between and frictionally engaged by said glass sections, means on the 95 ends of the auxiliary frame for the reception of said cleats to retain them in position, and a molding covering the cleats.

3. A display sign comprising a main frame, an auxiliary frame having a rabbet 100 and secured in the main frame adjacent its forward margin, a pair of glass sections engaging said rabbet, longitudinal cleats carrying blocks bearing upon the margin of one of the glass sections to insure pressure 105 between it and the other glass section, an advertising exhibit between and frictionally engaged by said glass sections, outstanding loops carried by the auxiliary frame for the reception of the ends of the cleats, devices 110 engaging between the outer portions of the loops and the ends of the cleats to insure constant pressure upon the glass sections, and a molding covering the cleats.

In testimony whereof he affixes his signature. 115

FRED A. LUND.
